UNITED STATES PATENT OFFICE.

ELMER J. SNAPP, OF STRASBURG, VIRGINIA.

MATCH-SAFE.

1,217,649.

Specification of Letters Patent. Patented Feb. 27, 1917.

Application filed March 4, 1916. Serial No. 82,146.

To all whom it may concern:

Be it known that I, ELMER J. SNAPP, a citizen of the United States, residing at Strasburg, in the county of Shenandoah and 5 State of Virginia, have invented certain new and useful Improvements in Match-Safes, of which the following is a specification.

This invention relates to an improved match safe and the principal object of the 10 invention is to provide a match safe having an improved delivery mechanism and to further provide a match safe having improved striking mechanism positioned with respect to the delivery mechanism so that as the 15 match is conveyed from the reservoir to the delivery opening, it will pass across the striking surface and thus be lighted when delivered.

Another object of the invention is to provide 20 the delivery cylinder with improved means for moving the match longitudinally of the same as the cylinder rotates to bring the match holding pocket into registry with the outlet opening, a cam strip being provided 25 to guide the movement of the abutment pin positioned to engage the match in the match holding pocket of the cylinder.

Another object of the invention is to provide 30 an improved type of match receiving tray outside the delivery opening of the match safe, the tray being provided with a perforated bottom so that the match will remain lighted after being delivered upon the tray.

Another object of the invention is to provide 35 an improved type of actuating mechanism for the shaft carrying the delivery cylinder, the actuating mechanism being yieldably held in one position by resilient means.

Another object of the invention is to provide 40 improved means for agitating the matches in the reservoir or hopper to permit the matches to be shaken loose in case they should become jammed in the reservoir.

Another object of the invention is to so 45 construct this match safe that a cigar cutter may be connected with the same and to further so construct the match safe, that the striking surface may be removed from the 50 outside when necessary and either cleaned and put back in place or a new one put in place.

This invention is illustrated in the accompanying drawings, wherein:

Figure 1 is a perspective view of the improved match safe. 55

Fig. 2 is a vertical sectional view through the match safe.

Fig. 3 is a view similar to Fig. 2 but taken 60 at right angles to the same.

Fig. 4 is a sectional view taken along the line 4—4 of Fig. 3.

Fig. 5 is a sectional view through the delivery cylinder.

Fig. 6 is a fragmentary perspective view 65 showing the delivery cylinder and striking surface.

This match safe includes a housing 10 which is supported by the feet 11 and is provided with an inner chamber 12, the upper 70 chamber of which is divided by the plate or partition 13 to provide a hopper or reservoir 14 in which the matches 15 will be placed. A window 16 is provided so that it can be readily ascertained when it is necessary to 75 refill the match safe and a cover 17 is hingedly connected with the receptacle or housing as shown at 18 and releasably held in a closed position by means of the hasp 19. Within this hopper 14 there is provided an 80 agitating plate 20 which is formed of resilient material secured by the screws or other fasteners 21 and having its free end portion extending over the opening 22 so that the crank arm 23 of crank shaft 24 can engage 85 the agitator strip or plate thus moving the plate when the crank shaft is rocked through the medium of handle or lever 25. A bracket 26 is provided to limit the movement of the lever handle 25 thus preventing 90 this rocker shaft 24 from being rotated in either direction for too great an extent.

The delivery cylinder 27 is positioned in the chamber 12 beneath the hopper 14 and is rigidly mounted upon a shaft 28 which 95 shaft extends through the wall of the receptacle 10 into the drum housing 29 mounted upon one side of the receptacle. A drum 30 is rigidly mounted upon this shaft within the drum housing 29 and is provided with a groove 31 to receive the strap or actuating line 32, the outer end of which is enlarged to provide a head 33 preventing the line from moving entirely into the housing 100

when the drum is returned to its normal position by means of spring 34. This drum is further provided with an abutment shoulder 35 for engagement with the abutment lug or block 36 thus limiting the rotary movement of the drum and preventing the delivery cylinder 27 from being rotated in the chamber 12 beyond the desired point.

This delivery cylinder is provided with a longitudinally extending slot forming a pocket 37 in which there is positioned a rod 38 carrying a spring 39 which spring engages a bracket 40 slidably mounted upon the rod 38. This bracket 40 constitutes a finger for moving a match longitudinally in the pocket to bring its striking head into engagement with the striking surface 41 and engages a cam strip 42 which extends as shown in Fig. 3 so that the movement of the latch in the pocket 37 will be gradual and the head of the match brought into engagement with the striking surface 41 at the proper time and with the proper amount of pressure. As this match is drawn across the striking surface the match will be ignited and the lighted match will then be moved through the outlet opening or slot 43 onto the perforated bottom of the tray 44. Upon releasing the actuating line 33, the spring 34 will rotate the drum 30 in the opposite direction thus winding the line upon the drum and returning the delivery cylinder to the normal position.

The operation of this match safe is as follows:—

The matches are placed in the hopper as shown in Fig. 2 and the machine is ready for use. In order to deliver a match from the safe, the line or strap 32 is drawn outwardly thus rotating the delivery cylinder and bringing the pocket to the elevated position for receiving a match from the hopper. As the cylinder rotates, the bracket is moved in the pocket by means of the cam strip and will then be in a position to engage the end of the match. Upon releasing the strap, the spring 34 will contract, thus rotating the delivery cylinder in the opposite direction. As this delivery cylinder rotates, the spring 39 draws the bracket along the rod 38 and the match is moved toward the striking surface across which it passes thus igniting the match. Upon reaching the outlet slot 43, the match will be forced through the same into the pan. This striking surface 41 is preferably in the form of a piece of roughened metal set in a recess 45 and releasably held in place by the slide 46. A cigar cutter 47 is connected with the front wall of this match safe so that cigars may be cut and includes a drawer 48 to receive the ends of the cigars which are cut off.

What is claimed is:—

1. A match safe comprising a housing having a chamber therein, a shaft extending

through the chamber of said housing and through one wall thereof, a drum housing inclosing the outer end of said shaft, a partition in said chamber forming a hopper above said shaft, a delivery cylinder mounted upon said shaft within said chamber and provided with a longitudinally extending groove forming a pocket, a rod in said pocket, a bracket slidably mounted upon said rod, a spring mounted upon said rod and engaging said bracket to yieldably hold the bracket in a normal position, a cam strip extending in said chamber to guide the longitudinal movement of said bracket as said cylinder rotates, a drum mounted upon said shaft within said drum housing, resilient means engaging said drum to yieldably hold the same in a normal position, means for rotating said drum, and a striking surface carried by said housing adjacent an outlet formed therein.

2. A match safe comprising a receptacle having a chamber formed therein, a partition in the chamber providing a hopper in the upper portion thereof, a shaft rotatably carried by said receptacle and extending through said chamber, a delivery cylinder carried by said shaft within said chamber beneath said hopper and provided with a longitudinally extending groove forming a pocket, a cam strip extending through said chamber transversely of said cylinder, a bracket slidably mounted in said pocket and having its outer end portion engaging said cam strip, resilient means yieldably holding said bracket in engagement with said cam strip, and means for rotating said shaft to rotate said cylinder, said bracket moving in said pocket when said cylinder is rotated to move a match out of the pocket through an outlet opening in said receptacle.

3. A match safe comprising a receptacle, a partition in said receptacle providing a hopper, a delivery cylinder rotatably mounted in said receptacle beneath said hopper and provided with a match receiving pocket, said receptacle being provided with an outlet, and means for moving a match longitudinally in said pocket and out of the outlet opening of said receptacle as the cylinder rotates.

4. A match safe including a receptacle, a delivery cylinder rotatably mounted in said receptacle and provided with a match receiving pocket moving into registry with an outlet opening in the receptacle when said cylinder rotates, and means moving a match in said pocket toward one end of the cylinder and through the outlet opening as said cylinder rotates.

5. A match safe including a receptacle provided with an outlet opening, a scratching element mounted adjacent said outlet opening, delivery means rotatably mounted in said receptacle and provided with a match

holding pocket moving into registry with the outlet opening when the delivery means is rotated, and means for moving a match in said pocket into engagement with the 5 striking element and out of said receptacle through the delivery opening as said delivery means rotates.

6. A match safe including a receptacle provided with an outlet, a scratching element mounted adjacent the outlet, movably mounted delivery means, and means for moving a match carried by said delivery means into engagement with the striking means and out of the outlet as said delivery 15 means moves.

7. A match safe including a receptacle, a delivery cylinder rotatively mounted in said receptacle and provided with a match receiving pocket, said receptacle being provided with an outlet, and means for moving 20 a match through the pocket and out of the outlet opening of said receptacle as the cylinder rotates.

In testimony whereof I affix my signature in presence of two witnesses.

ELMER J. SNAPP.
